UNITED STATES PATENT OFFICE.

WILLIAM GORDON, OF BOSTON, MASSACHUSETTS.

MACHINE FOR LAYING CHANNEL-FLAPS OF BOOT OR SHOE SOLES.

SPECIFICATION forming part of Letters Patent No. 426,374, dated April 22, 1890.

Application filed November 14, 1889. Serial No. 330,255. (No model.)

To all whom it may concern:

Be it known that I, WILLIAM GORDON, of Boston, in the county of Suffolk and State of Massachusetts, have invented certain new and 5 useful Improvements in Devices for Laying Channel-Flaps of Boot or Shoe Soles, of which the following is a specification.

This invention has for its object to provide simple and efficient means for pressing down 10 the channel-flaps of machine-sewed boot or shoe soles after the stitching operation has been performed; and it consists in a wheel or 15 disk and a series of spring-supported studs fitted to slide in radial sockets in said wheel, their outer ends being rounded and presenting 20 a series of independent convex rubbing-surfaces, which are caused by the supporting-springs to bear with a yielding pressure against a sole presented to the periphery of the wheel, as I will now proceed to describe and claim.

Of the accompanying drawings, forming a part of this specification, Figure 1 represents 25 a side elevation of my improved flap-laying wheel, showing its supporting-shaft and the bearings therefor. Fig. 2 represents an end elevation of the same. Fig. 3 represents a section on line 3 3, Fig. 2.

The same letters of reference indicate the same parts in all the figures.

30 In the drawings, *a* represents the wheel, which is preferably composed of the web or body portion 2 and the circular rim or peripheral portion 4, offset from the web, the wheel being affixed to a shaft *b*, which is journaled 35 in bearings *c c* and rotated by any suitable power.

In the rim 3 are drilled a series of radial sockets *d*, in which are fitted a series of studs *e*, said studs being metal cylinders adapted to 40 slide freely in the sockets *d* and provided with convex outer ends.

Springs *f* are interposed between the inner ends of the studs and the bottoms of the sock-

ets *d*, said springs pressing the studs outwardly. The studs are provided with shanks 45 *e'*, which pass through orifices in the bottoms of the sockets *d* and are provided with heads or enlargements *e*², bearing against the inner surface of the rim 3, said heads preventing the studs from being forced out from their 50 sockets by the springs *f*. Any other suitable means may be employed, however, to prevent the removal of the studs, my invention not being limited in this particular to the devices here shown. 55

It will be seen that the outer ends of the studs *e* constitute a series of convex metallic rubbing-surfaces located in close proximity to each other, so that collectively they will act on a surface of the same width as the distance 60 between the outer edges of the outer rows of studs. The studs, being independent of each other, are enabled to yield independently, so that they can conform to the inequalities and curves of the sole-bottom on which they act. 65 The convex form of the outer ends of the studs enables them to rub the flap down smoothly without scratching or injuring the same.

I claim—

The improved flap-laying device, composed 70 of the wheel having radial sockets, studs fitted to slide independently in said sockets, springs within the sockets supporting the studs, and means for preventing the removal of the studs from the sockets, the studs having 75 convex outer ends constituting independent rubbing-surfaces, as set forth.

In testimony whereof I have signed my name to this specification, in the presence of two subscribing witnesses, this 4th day of 80 November, A. D. 1889.

WILLIAM GORDON.
